CIRCUIT INTERRUPTER

Raymond H. Leitzel, Forest Hills, Pa., assignor to
Westinghouse Electric Corporation, East Pitts-
burgh, Pa., a corporation of Pennsylvania

Application August 15, 1946, Serial No. 690,626

13 Claims. (Cl. 200—82)

1

This invention relates to circuit interrupters and more particularly to circuit interrupters of the types that are operated by compressed gas.

An object of the invention is to provide a circuit interrupter of the compressed gas operated type having an electromagnetically operated pilot valve for controlling the admission of compressed gas to operate said interrupters, with a low voltage trip device for operating said pilot valve.

Another object of the invention is to provide a circuit interrupter having an electromagnetically operated pilot valve operable in response to overload currents for controlling the admission of compressed gas to operate said interrupter, with a low voltage responsive means for operating said pilot valve.

Another object of the invention is to provide an interrupter having a fluid motor operated mechanism for operating said breakers to open and closed position and a single pilot valve for controlling the admission of compressed gas to said motor to operate the interrupter to open position with means for operating said pilot valve in response to overload currents and also in response to low voltage conditions.

The novel features that are considered characteristic of the invention are set forth in particular in the appended claims. The invention itself, however, both as to structure and operation, together with additional objects and advantages thereof, will be best understood from the following detailed description of an embodiment thereof when read in conjunction with the accompanying drawings; in which—

Fig. 1 is a side elevational view, partly in section, showing a compressed gas operated circuit interrupter embodying the principles of the invention.

Fig. 2 is a front elevational view of the compressed gas operating mechanism for operating the circuit interrupter to open and closed positions.

Fig. 3 is an enlarged side elevation view showing the under voltage trip device.

Fig. 4 is an elevational view, partly in section, showing the compressed gas operating mechanism for the circuit interrupter illustrated in Fig. 1.

The invention is illustrated as applied to a circuit breaker of the type disclosed in the U. S. Patent No. 2,401,008, issued May 28, 1946, to Leon R. Ludwig and Benjamin P. Baker, and assigned to the assignee of the present invention.

Referring to Figs. 1 and 2 of the drawings, a storage tank 6 mounted within a metal frame 7 is provided for storing compressed gas. Extending

2

from the top of the tank 6 are three flanged conduits 8 which, in turn, carry metallic valve casings 10. A tubular insulator 12 having a gas passage therethrough is mounted on the upper end of each valve casing 10, and an arc chute support 14 (Fig. 1) also of insulating material is secured to the upper end of the tubular insulator 12. The support 14 has mounted thereon a stationary contact 16 provided with an external terminal connection 18. An arc chute 22 is secured by means of bolts 24 to the support 14. Braces 25 of insulating material (only one being shown) connect the frame 7 and the insulating arc chute supports 14.

15 A movable contact blade 28 is provided for cooperating with the stationary contact 16. One arm 30 of the contact blade 28 is bifurcated and the two arms thereof are pivoted at 32 to a conducting bracket 34 securely clamped about the tubular insulator 12. The pivotal connection 32 is of the high-pressure type in order to provide a good electrical connection at all times between the bifurcated contact arm 30 and the mounting bracket 34. A terminal connector 36 extends 20 from the right hand side (Fig. 1) of the bracket 34 and serves, together with the terminal connector 18 to connect the circuit interrupter in an electrical circuit. The circuit through the breaker extends from the terminal 18 through 25 the stationary contact 16, the movable contact blade 28, contact arms 30 and the bracket 34 to the terminal 36.

An operating mechanism of the compressed gas type, indicated generally at 38 (Figs. 1, 2 and 4), is 30 provided to actuate the three movable contact blades 28 about the pivots 32 to open and close the contacts. The operating mechanism 38 is mounted within the frame 7 and includes an operating cylinder 40 (Figs. 1, 2 and 4), a piston 42 (Fig. 4) reciprocably movable therein, and a connecting rod 44 attached to the piston and extending vertically through an air-tight opening in the upper end of the cylinder 40. The connecting rod 44 is connected by a pair of spaced 35 links 46 to a crank arm 48 (Fig. 2) secured to a cross shaft 50 which is journaled in brackets 52 mounted on the side of the pressure tank 6.

Crank arms 54 (Figs. 1 and 2), secured at spaced intervals to the cross shaft 50, are connected by 40 insulating operating rods 56 to the movable contact arms 30 for the three poles of the breaker.

If compressed gas is admitted to the cylinder 40 above the piston 42 the piston will be moved downward in the cylinder and the connecting rod 44 will actuate the crank arm 48

and the cross shaft counterclockwise. This movement of the shaft 50 rotates the crank arms 54 in the same direction, and, through the connecting rods 56, rotate the movable contact arms 30 about their pivots 32 toward open position.

Each of the crank arms 54 (Fig. 1) is provided with a cam surface 58 which cooperates with an anti-friction roller 60 carried by one arm of a bell crank 62. The bell crank 62 is pivoted at 64 on a suitable support and the other arm of the bell crank is pivotally connected to a valve stem 66 which, at its other end, carries a blast valve (not shown) seated within the valve casing 10. The cam surface 58 controls the blast valve to admit a blast of arc-extinguishing gas through the passage in the tubular insulator 12 at the separating contacts when the arc is drawn. The arc drawn between the contacts is thus blown upwardly into the arc chute 22 and then extinguished by the blast of gas from the pressure tank 6. The cams 58 on the crank arms 54 are so shaped that the blast valves (not shown) are permitted to close when the moving contacts have reached full open position so as to shut off the blast of compressed gas.

Upon admission of compressed gas to the cylinder below the piston 42 (Fig. 4) the piston will be moved upwardly in the cylinder reversing the above described operation to operate the movable contacts 28 to closed position. As the mechanism arrives at the closed circuit position, the crank arms 54 engage stops 55. In this position, the crank arms 54 and their connecting rods 56 form slightly overcenter toggles which maintain the movable contacts positively locked in the closed circuit position.

In order to effect opening and closing of the circuit interrupter, two control valves indicated generally at 70 and 72 (Figs. 2 and 4) are provided to control the flow of compressed gas from the storage tank 6 to the operating cylinder 40. The control valve assemblies 70 and 72 are secured to the operating cylinder 40 and rest upon and are secured respectively to flanges 74 and 76 of two conduits 78 and 80 which extend into and communicate with the storage tank 6. The valves 70 and 72 which respectively control the flow of gas to the operating cylinder 40 to open and close the circuit interrupter are similar in construction. The opening control valve 70, shown in section in Fig. 4 comprises a valve casing 104, the lower face of which rests on the flange 74 of the conduit 78. The valve casing 104 is provided with a valve seat 106 with which a valve 108 of the poppet type cooperates to open and close the air passage leading from the storage tank 6 to the cylinder 40 above the piston 42. The valve 108 is provided with a valve stem 110 having a washer 112 secured to the upper end with which a spring 114 cooperates to normally bias the valve closed. The inner chamber of the valve casing 104 communicates, by means of a passage 116 to the upper end of the cylinder 40. The valve casing 104 is also provided with a passage 118 which communicates with the storage tank and a valve chamber 120 in an auxiliary valve casing 122.

An electromagnetically operated pilot valve 124 communicates by means of a passage 126 with a piston chamber 128 at the upper end of the opening valve casing 104. A piston 130 operable in the cylinder 128 is normally held in raised position by a spring 132. The lower end of the skirt of the piston 130 extends to a plurality of ports 134 passing radially through the side of the valve

casing 104. When the piston 130 is in the raised position (Fig. 4) the ports 134 are open, thereby connecting the space in the operating cylinder 40 above the piston 42 to atmosphere. Downward movement of the piston 130 closes the ports 134 and thereby seals the passage 116 and the cylinder 40 from the atmosphere and moves the main valve 108 to open position thus admitting compressed gas to the cylinder 40 above the piston 42 to operate the interrupter to open position.

The pilot valve 124 is actuated downwardly to open position by an electromagnet 136 mounted on the auxiliary valve casing 122. The electromagnet may be energized from any suitable source of electrical energy none being shown. A spring 138 is provided to close the pilot valve upon deenergization of the electromagnet 136.

When the interrupter is in the closed position, the operating mechanism including the piston 42 is in the position in which it appears in Fig. 4. With the mechanism in the closed position, if an overload occurs the electromagnet 136 is energized to open the pilot valve 124, admitting compressed gas to the piston chamber 128 of the opening valve. The piston 130 is thereupon moved downwardly closing the ports 134 and opening the valve 108 to admit compressed gas to the cylinder 40 above the piston 42. The piston 42 is thus moved downwardly to actuate the movable contacts 28 to the open circuit position in the previously described manner. The control circuit (not shown) for energizing the electromagnet 136 may be controlled by an opening relay and by an auxiliary switch 140 (Fig. 2) of any suitable construction mounted on the tank 6 and operated by means of a link 142 by the shaft 50.

It is also desirable to cause opening of the interrupter in the event of loss of voltage or failure of voltage in the control circuit. Means comprising an electromagnet indicated generally at 144 (Figs. 1, 2, 3 and 4) is connected across the control circuit and normally energized by the voltage in the control circuit. The electromagnet 144 comprises a U-shaped core member 146 (Fig. 3) fixedly mounted on a pair of spaced rods 148 supported in a bracket 150 secured to the frame 7 by any suitable means as, for instance, by welding. An energizing coil 152 surrounds one leg of the core members and an armature 154 is pivotally mounted on a pin 156 (Fig. 3) supported in side plates 158 (only one being shown) secured to the sides of the other leg of the core member 146. Rigidly secured to opposite sides of the armature 154 are identical plates 160 each of which carries a spring stud 162 to which are anchored the lower ends of a pair of springs 164. The upper ends of the springs 164 are hooked over the ends of a shaft 166 supported in a pair of spaced plates 168 mounted on the rods 148 and disposed one on each side of the core member 146.

The plates 160 which are secured to and move with the armature 154 are provided with vertically disposed slots 170 (Fig. 3) through which project the ends of a pin 172 carried by the upper end of a trip rod 174. The enlarged lower end of the trip rod 174 normally rests on a button 176 which, when depressed, mechanically operates the pilot valve 124 to the open position. The weight of the trip rod 174 does not normally apply force enough to the button 176 to operate the pilot valve. When the voltage in the control circuit drops a predetermined amount or fails

entirely, the electro-magnet 144 is deenergized and releases the armature 154, which, accelerated by the springs 164, moves in a counterclockwise direction about the pivot 156. During this movement the upper ends of the slots 170 in the plates 160 strike the pins 172 and thrust the trip rod 174 downwardly to operate the button 176 and effect opening of the pilot valve 120. Opening of the pilot valve, as set forth previously, causes opening of the valve 108 and admission of compressed gas to the cylinder 40 above the piston to actuate the interruption to the open position.

The armature 154 is moved to attracted position when the interrupter mechanism moves to the open position. The means for resetting the armature 154 comprises an adjustable screw 178 (Fig. 3) mounted in a projection 180 rigidly mounted on the shaft 50 and locked in the adjusted position by means of a lock nut 182. These parts are shown in the closed position of the interrupter in dot and dash lines in Fig. 3 at 178', 180' and 182'. When the interrupter moves to open position the shaft 50 rotates counterclockwise during which movement the screw 178 engages a resilient member 184 secured by means of rivets to a latch member 186 which is in turn rigidly secured to the armature 154. Continued counterclockwise movement of the shaft 50 after the screw 178 engages the resilient member 184, rotates the armature 154 clockwise about its pivot 162 to the attracted position in which it appears in Fig. 3.

Means is provided to latch the armature 154 in the attracted position until normal voltage is restored to the control circuit. This means comprises a latch 188 pivotally mounted on the shaft 166 and connected by means of a pin and slot connection 197-199 to a link 190 having its lower end pivotally connected to an arm 192 secured to the shaft 50 for movement therewith. In the closed position of the interrupter the parts assume the positions indicated by dot and dash lines at 188', 190' and 192' respectively. In this position the latch 188 is out of engagement with the latch member 186 on the armature 154 so that the armature 154 may function in the above described manner to effect opening of the interrupter in the event of loss of voltage in the control circuit. When the interrupter moves to the open position and the shaft 50 rotates counterclockwise to the position shown by full lines in Fig. 3, the arm 192 acts through the link 190 to move the latch 188 to engage a latching notch 194 therein into engagement with the end of the latch member 186, thus preventing movement of the armature 154 and the trip rod 174 to tripping position until normal voltage is restored to the control circuit or the interrupter is actuated to the closed position. Movement of the shaft 50 to close the interrupter raises the latch 180 to the position shown at 188' unlatching the armature in preparation for a subsequent low voltage tripping operation. Due to the pin and slot connection 197-199 the latch 188 does not disengage the latch member 186 until near the end of the closing movement of the mechanism thus preventing tripping movement of the armature 154 until the breaker is substantially in the closed position.

The interrupter is operated to the closed position by operating the closing valve 72 (Figs. 2 and 4) to admit compressed gas to the cylinder 40 below the piston 42. This causes the piston to move upwardly reversing the movement of

the mechanism and moving the movable contact arms 30 to closed position. The closing valve 72 is identical with the valve 70 for effecting opening of the interrupter. The valve 72 is provided with an electromagnet 196 (Fig. 2) which, when energized from any suitable source of electrical current, opens a pilot valve 198 to admit compressed gas to open the closing valve 72 which admits compressed air to the cylinder 40 below the piston 42 to close the interrupter in the manner previously described.

From the foregoing description it will be apparent to those skilled in the art to which this invention appertains that there is provided a novel low voltage trip device which operates a pilot valve, common to both the overload and under voltage trip devices, to effect opening of the interrupter.

Having described a preferred embodiment of the invention in accordance with the patent statutes, it is to be understood that various changes and modifications may be made therein without departing from some of the essential features of the invention. It is, therefore, desired, that the language of the appended claims be given as reasonably broad interpretation as the prior art permits.

I claim as my invention:

1. In a circuit interrupter, separable contacts, operating mechanism therefor comprising a cylinder and a piston operable therein for moving said contacts to open and closed positions, a source of gas under pressure, an opening control valve operable by compressed gas to admit compressed gas to said cylinder to cause said piston to move to open position, a pilot valve operable to admit compressed gas to said control valve to operate said control valve, electroresponsive means operable in response to overload currents to operate said pilot valve, an undervoltage device operable in response to predetermined voltage conditions to operate said pilot valve, and means preventing operation of said undervoltage device during closing operations of said circuit interrupter.

2. In a circuit interrupter, separable contacts, operating mechanism therefor comprising a cylinder and a piston operable therein for moving said contacts to open and closed positions, a source of gas under pressure, an opening control valve operable by compressed gas to admit compressed gas to said cylinder to cause said piston to move to open position, a pilot valve operable to admit compressed gas to said control valve to operate said control valve, electroresponsive means operable in response to overload currents to operate said pilot valve, and an undervoltage device operable in response to predetermined voltage conditions to operate said pilot valve, and means operable by said operating mechanism when said mechanism moves to open position to reset said undervoltage device.

3. In a circuit interrupter, separable contacts, operating mechanism therefor comprising a cylinder and a piston operable therein for moving said contacts to open and closed positions, a source of gas under pressure, an opening control valve operable by compressed gas to admit compressed gas to said cylinder to cause said piston to move to open position, a pilot valve operable to admit compressed gas to said control valve to operate said control valve, electroresponsive means operable in response to overload currents to operate said pilot valve, and an undervoltage device operable in response to predetermined volt-

age conditions to operate said pilot valve, means operable by said operating mechanism when said mechanism moves to open position to reset said undervoltage device, and means operable by said operating mechanism to restrain said undervoltage device in reset position during a closing operation.

4. In a circuit interrupter, separable contacts, operating mechanism therefor comprising a cylinder and a piston operable therein for moving said contacts to open and closed positions, a source of gas under pressure, an opening control valve operable by compressed gas to admit compressed gas to said cylinder to cause said piston to move to open position, a pilot valve operable to admit compressed gas to said control valve to operate said control valve, electro-responsive means operable in response to overload currents to operate said pilot valve, and an undervoltage device comprising an electromagnet having an armature operable in response to predetermined voltage conditions to operate said pilot valve, and means operable by said operating mechanism to reset said armature to operative position.

5. In a circuit interrupter, separable contacts, operating mechanism therefor comprising a cylinder and a piston operable therein for moving said contacts to open and closed positions, a source of gas under pressure, an opening control valve operable by compressed gas to admit compressed gas to said cylinder to cause said piston to move to open position, a pilot valve operable to admit compressed gas to said control valve to operate said control valve, electroresponsive means operable in response to overload currents to operate said pilot valve, and an undervoltage device comprising an electromagnet having an armature operable in response to predetermined voltage conditions to operate said pilot valve, means operable by said operating mechanism to reset said armature to operative position, and means operable by said operating mechanism to latch said armature in operative position during a closing operation.

6. In a circuit interrupter, separable contacts, operating mechanism therefor comprising a fluid motor for operating said contacts to open and closed position, a source of gas under pressure, an inlet valve operable by compressed gas to admit compressed gas to said motor to effect opening of said interrupter, an overload trip device, an undervoltage trip device, a pilot valve operable by said overload trip device under certain conditions and also operable by said undervoltage trip device under certain other conditions to admit compressed gas to operate said inlet valve to thereby effect opening of said interrupter, and means for preventing operation of said pilot valve by said undervoltage device during a closing operation of said interrupter.

7. In a circuit interrupter, separable contacts, operating mechanism therefor comprising a fluid motor for operating said contacts to open and closed position, a source of gas under pressure, an inlet valve operable by compressed gas to admit compressed gas to said motor to effect opening of said interrupter, an overload trip device, an undervoltage trip device, a pilot valve operable by said overload trip device under certain conditions and also operable by said undervoltage trip device under certain other conditions to admit compressed gas to operate said inlet valve to thereby effect opening of said interrupter, and

means operated by said operating mechanism to reset said undervoltage trip device.

8. In a circuit interrupter, separable contacts, operating mechanism therefor comprising a fluid motor for operating said contacts to open and closed position, a source of gas under pressure, an inlet valve operable by compressed gas to admit compressed gas to said motor to effect opening of said interrupter, an overload trip device, an undervoltage trip device, a pilot valve operable by said overload trip device under certain conditions and also operable by said undervoltage trip device under certain other conditions to admit compressed gas to operate said inlet valve to thereby effect opening of said interrupter, means operable by said operating mechanism to reset said undervoltage trip device, and means for retaining said undervoltage trip device in reset position until said interrupter is closed.

20 9. In a circuit interrupter, separable contacts, operating mechanism therefor comprising a fluid motor for operating said contacts to open and closed position, a source of gas under pressure, an inlet valve operable by compressed gas to admit compressed gas to said motor to effect opening of said interrupter, an overload trip device, an undervoltage trip device, a pilot valve operable by said overload trip device under certain conditions and also operable by said undervoltage trip device under certain other conditions to admit compressed gas to operate said inlet valve to thereby effect opening of said interrupter, and means operable by said operating mechanism during an opening movement to engage and move said undervoltage trip device to reset position.

10 10. In a circuit interrupter, separable contacts, operating mechanism therefor comprising a fluid motor for operating said contacts to open and closed position, a source of gas under pressure, an inlet valve operable by compressed gas to admit compressed gas to said motor to effect opening of said interrupter, an overload trip device, an undervoltage trip device, a pilot valve operable by said overload trip device under certain conditions and also operable by said undervoltage trip device under certain other conditions to admit compressed gas to operate said inlet valve to thereby effect opening of said interrupter, means operable by said operating mechanism during an opening operation to engage and move said undervoltage trip device to reset position, and latch means operable by said operating mechanism during an opening operation to engage and restrain said undervoltage trip device in the reset position during a closing operation of said breaker.

11. In a circuit interrupter, separable contacts, operating means therefor comprising a fluid motor for operating said contacts to open and closed positions, a source of compressed gas, an inlet valve operable by compressed gas to said motor to admit compressed gas to said motor to effect opening of said interrupter, a pilot valve operable to admit compressed gas to operate said inlet valve, a trip device comprising electroresponsive means operable in response to overload currents for operating said pilot valve, an undervoltage trip device comprising an electromagnet having an armature normally held in attracted position and releasable in response to a drop in voltage, means operable by said armature when said armature is released to mechanically operate said pilot valve, and latch means restraining said armature against operation during closing operations of

said interrupter irrespective of variations in voltage.

12. In a circuit interrupter, separable contacts, operating means therefor comprising a fluid motor for operating said contacts to open and closed positions, a source of compressed gas, an inlet valve operable by compressed gas to admit compressed gas to said motor to effect opening of said interrupter, a pilot valve operable to admit compressed gas to operate said inlet valve, a trip device comprising electroresponsive means operable in response to overload currents for operating said pilot valve, an undervoltage trip device comprising an electromagnet having an armature normally held in attracted position and releasable in response to a drop in voltage, and means operable by said armature when said armature is released to mechanically operate said pilot valve, and means operable by said operating means during an opening movement thereof for engaging and resetting said armature to attracted position.

13. In a circuit interrupter, separable contacts, operating means therefor comprising a fluid motor for operating said contacts to open and closed positions, a source of compressed gas, an inlet valve operable by compressed gas to admit compressed gas to said motor to effect opening of

said interrupter, a pilot valve operable to admit compressed gas to operate said inlet valve, a trip device comprising electroresponsive means operable in response to overload currents for operating said pilot valve, an undervoltage trip device comprising an electromagnet having an armature normally held in attracted position and releasable in response to a drop in voltage, and means operable by said armature when said armature is released to mechanically operate said pilot valve, means operable by said operating means during an opening movement thereof for engaging and resetting said armature to operative position, and means operable by said operating mechanism during an opening movement for engaging and restraining said armature in operative position during a closing operation.
